CHARGING STRUCTURE FOR TRANSIT
MIXERS

Chris Gerst, Detroit, Mich., assignor, by mesne assignments, to Le Roi Company, Milwaukee, Wis., a corporation of Delaware.

Application January 9, 1952, Serial No. 265,601

11 Claims. (Cl. 259—161)

1

This invention relates in general to concrete mixers, and, more particularly, to truck or transit mixers in which a mixing drum with a charging and discharging opening axially at its rear end is rotatably mounted on the chassis of a truck for rotation about a preferably inclined axis, the mixing drum receiving through its opening the ingredients for a concrete mixture and discharging through said opening the mixed concrete. These truck or transit mixers have their mixing drum generally associated with a shiftable charging hopper positioned to direct the concrete making ingredients through the drum opening, which charging hopper generally includes a closure plate or door member rotatably mounted on the discharge end of the hopper to permit closing of the drum opening for charging and mixing operations and joint shifting of hopper and door member in a direction away from the drum opening to permit free discharge of mixed concrete from the mixing drum.

The present invention is specifically concerned with truck mixers having their charging hoppers constructed and arranged in the manner described above and has for its principal object the provision of new and improved supporting means for the shiftable charging hopper of a transit mixer, which supporting means are of rugged construction, permit ready and easy shifting of the hopper into cooperating position with respect to the charging and discharging opening of the mixing drum, and are mounted on the frame of the transit mixer so as to readily absorb road shocks without disturbing the cooperating position between the mixing drum opening and the hopper.

This general object of the invention is attained by yieldingly supporting the hopper structure of a transit mixer on the web portion of a U-shaped frame structure shiftably mounted for reciprocatory movements in axial alignment with the axis of the mixer drum, the frame structure including flanges guided in parallelly arranged roller guides mounted on brackets attached to the frame of the transit mixer and arranged parallel to the axis of the mixing drum in diametrically opposed relation with respect to the charging opening of the mixer drum.

Another object of the invention, therefore, is the provision of a truck or transit mixer embodying a hopper structure supported by the web portion of a U-shaped shiftable frame, the flanges of which are shiftably engaged with roller guides mounted on the frame of the truck mixer in symmetrical, parallel relation with respect to each

2

other and the axis of the mixer drum to position the roller guides in diametrically opposed relation with respect to the charging opening of the mixing drum of the transit mixer.

A further object of the invention is the provision of a truck mixer embodying a hopper structure of the type referred to above in which the hopper structure embodies a hopper and a door member rotatably mounted thereon in which the hopper structure is pivotally supported on the web portion of the U-shaped frame structure by extensions which have pivotal connections with the hopper arranged in diametrically opposed relation with respect to the charging opening of the mixing drum and in which the hopper additionally is yieldingly coupled with the web portion of the U-shaped frame structure to yieldingly absorb road shocks imparted to the mixing drum and hopper without disturbing their cooperating position present in mixing and charging operations.

Still other important objects of the invention are to provide a truck mixer with a hopper arrangement adapted to permit rapid and inexpensive charging and discharging operations of the mixing drum of the truck mixer, the hopper arrangement being of as simple a design and low cost as possible and practical and efficient for all purposes intended.

Additional objects and novel features of construction, combinations and relations of parts by which the objects in view have been attained will appear and are set forth in detail in the course of the following specification.

The drawings accompanying and forming part of the specification illustrate a certain practical embodiment of the invention, but it will be apparent as the specification proceeds that the structure may be modified and changed in various ways without departure from the true spirit and broad scope of the invention.

In the drawings:

Fig. 1 is a fragmentary view of the upper rear end of a transit mixer with a hopper arrangement constructed in accordance with the invention, the hopper being shown in coordinated charging and mixing position with respect to the mixing drum;

Fig. 2 is a fragmentary view similar to Fig. 1, with the hopper shown in the discharge position of the mixing drum;

Fig. 3 is a fragmentary view of the rear end of the transit mixer shown in Fig. 1; and

Fig. 4 is a front elevation of the structure shown in Fig. 3;

Fig. 5 is a side view partly in section and with parts broken away of the upper rear end of the transit mixer shown in Figs. 3 and 4; and

Fig. 6 is a longitudinal sectional view on line 6—6 of Fig. 5;

Fig. 7 is a side view, partly in section and with parts omitted showing the mounting and sealing connection of the door structure on the discharge end of the hopper;

Fig. 8 is an enlarged, fragmentary, sectional view taken on line 8—8 of Fig. 4; and

Fig. 9 is an enlarged, fragmentary, sectional view taken on line 9—9 of Fig. 4.

Referring now more in detail to the exemplified form of the invention shown in the drawings, reference numeral 2 denotes a transit mixer drum rotating about a rearwardly, upwardly inclined axis. This mixing drum which includes at its rear frusto-conically shaped end 3 a circular, axially arranged charge and discharge opening 4 reinforced by a circular drip ring 5, is at its rear end rotatably supported on cradle rolls 6 mounted on a frame 7 in turn, as customary, supported on the chassis of a truck, not shown. Mixing drum 2 is rotated by suitable means, also not shown, to effect mixing of material charged thereinto with the assistance of generally spirally arranged blades mounted interiorly of the mixing drum and constructed to effect, on reversal of rotation of the drum, discharge of material from the drum through opening 4.

The mixing drum is charged through a funnel-like hopper 8 which is pivotally supported on a substantially U-shaped frame structure 9 shiftably engaged with supporting frame 7. Hopper 8 has attached to its discharge end 10 two transverse brackets 11 arranged at opposite sides of the hopper and provided with short, trunnion-like portions 12 journaled in bores 14 of supporting arms 15, which are extended from web 16 of U-shaped frame structure 9. This arrangement mounts hopper 8 symmetrically between the rod-like side member 17 of frame structure 9, which side members are slidably engaged with roller guides 18 attached to bracket members 19 mounted on symmetrically arranged uprights 20 of supporting frame 7 at opposite sides of mixing drum 2.

Roller guides 18 each consist of two spaced pairs of rollers 21, the rollers 22 of which include grooved rims 23 and are freely rotatably mounted on studs 24 attached to bracket members 19. Each pair of rollers has its rollers 22 spaced from each other to properly guide the respective side member 17 of frame structure 9 and each two cooperating pairs of rollers are spaced from each other. The thus constructed roller guides are arranged in a plane including the axis of the mixing drum to guide the hopper supporting frame structure 9 toward and away from material transfer opening 4 in axial alignment with the axis of the mixing drum.

Hopper 8 which, as described above, is pivotally supported in supporting arms 15 extended in the plane of U-shaped frame structure 9, is additionally yieldingly coupled with web 16 of the frame structure by a member 25 including a short rod 26 which has its one end connected to an ear portion 27 on hopper 8 and is extended through the perforation 28 of an ear portion 29 on web 16. A spring arrangement 30, including two openings 31 and 32 on rod 26 yieldingly counteracts shifting of rod 26 in ear portion 29 in one or the other direction and permits yielding tilting of the hopper on its pivotal support to yieldingly adjust

the hopper with respect to the charge and discharge opening 4 of the mixing drum.

Discharge end portion 10 of hopper 8, which is smaller in diameter than opening 4 of mixing drum 2 to permit proper, unimpeded feeding of material thereinto, freely rotatably supports a closure member 33 including a dished, ring-shaped closure plate 34 and a short tubular discharge extension 35. Closure member 33 has its ring-shaped closure plate 34 and discharge extension 35 mounted on a combined bearing and sealing ring structure 36, the outer ring member 37 of which mounts discharge extension 35 and the inner ring member 38 of which encircles and is welded to discharge end portion 10 of hopper 8.

Outer ring member 37 is constructed of separate inner and outer ring elements 39 and 40 for purposes of assembly and disassembly which elements are sleeved upon each other and secured to each other by bolts 41. The inner ring element 39 has extended thereinto discharge extension 35 preferably welded thereto and the outer ring element 40 having angular cross section, is rigidly connected by its circumferential radial flange 42 to ring-shaped closure plate 34. Inner ring element 39 is constructed with an inclined, inner, annular sealing shoulder 43 arranged in the central portion thereof, an outer annular sealing shoulder 44 near one end wall and an annular groove 46 in said end wall. Outer ring element 40 includes a recessed bore 47 providing said element with an inner annular sealing shoulder 48 and additionally has extended from radial flange 42 a circumferential lateral flange 49.

Inner ring member 38 is constructed of separate, adjoining, inner and outer ring elements 50, 51 for purposes of assembly and disassembly, which elements are secured to each other by bolts 52. Inner ring element 50 is welded to discharge end portion 10 of hopper 8 and has an inner circumferential flange 53 arranged parallel to the axis of ring member 50. This circumferential flange includes an inclined end face 54 the plane of which extends parallel to the plane of annular shoulder 43 in inner ring element 39 to effect proper sealing contact between end face 54 and shoulder 43 when in contact with each other. Inner ring element 50, furthermore, includes an annular rib 55 adapted to fit and extend into annular groove 46 of inner ring element 39. The inner ring element 51 embodies a flanged tubular body 56 having a recessed bore 57 and is arranged between ring elements 39 and 40 of outer seal ring member 37. Tubular body 56 when positioned between ring elements 38 and 39 contacts with its inner wall the outer wall of inner ring element 39, annular sealing shoulder 44, and, furthermore, contacts with its one end wall sealing shoulder 48, with its outer wall the inner wall of recessed bore 47 in outer ring element 40, and with its flange 58 the outer face of radial flange 42 and the inner face of circumferential flange 49. The length of the body 56 of ring element 51 is substantial to effect proper bearing and sealing contact in extended areas of inner and outer ring members 39 and 40, which areas include oil or grease grooves hereinafter to be described and shouldered contact areas arranged at right angles to the extended contact areas.

The described combined bearing and sealing ring structure provides properly designed, extended, interengaged male and female bearing elements protected from contact with abrasive constituents of the concrete mixture by sealing means which are formed as parts of said struc-

ture and constructed to enclose the bearing surfaces of said bearing elements by extended sealing surfaces arranged parallel to the bearing surfaces. Smooth operation of the combined bearing and sealing ring structure is effected by lubricant forced to the bearing and the sealing surfaces from individual grease cups 59, 60, respectively, through individual channels 61, 62.

Shifting of hopper 8, closure member 33 and supporting frame structure 9 from charging position (see Fig. 1) to discharging position (see Fig. 2) is effected by rotation of a shaft 63 mounted in bearings 64 supported on bracket members 19. For such purpose shaft 63 rigidly mounts adjacent to bearings 64 two lever arms 65 which have their free ends 66 linked to web 16 of supporting frame structure 9 by longitudinally adjustable link members 67. Shaft 63 is coupled to worm wheel sector 68 of a worm drive 69, the worm supporting shaft 70 of which mounts a hand wheel 71 for manual rotation of shaft 63 and therewith shifting of hopper supporting frame structure 9.

When the hopper supporting frame structure is in its discharge position mixed concrete discharged through opening 4 from mixing drum 2 is discharged into symmetrically arranged funnel-like members 72 supported on stationary frame 7 which members in turn guide such concrete to a distributing chute 73.

The charging structure for transit mixers described herein in connection with the accompanying drawings embodies simple and efficient means for supporting and shifting the charging hopper and closure member of a mixer in proper position to the charge opening of its mixing drum, which means prevent misalignment of the closure member with respect to the charge opening of the mixer and permit limited angular movements as may be caused by road shocks, etc. between the mixing drum and closure member without destroying their proper alignment.

It is obvious that the illustrated and described form of the invention may be varied in detail of construction, as well as in the arrangement of parts, without departing from the spirit of the invention or the scope of the appended claims.

Having thus described my invention, what I claim is:

1. In a concrete mixer a supporting frame, a rotatable mixing drum mounted on said frame having an axial opening at one end through which the drum is charged and discharged, a shiftable hopper structure including a U-shaped frame with parallelly arranged legs, a charging hopper mounted on the said U-shaped frame to partly extend therethrough and an annular closure member rotatably mounted on said hopper arranged to align with the axial opening of the mixing drum and seal such opening when the hopper structure is shifted toward the mixing drum, and spaced roller track means supported by said supporting frame and extended in parallel, symmetrical relation with respect to the axis of the mixing drum, said roller track means engaged with the legs of the U-shaped frame to properly support the shiftable hopper structure and guide shifting of the frame, charging hopper and closure member of the shiftable hopper structure when shifted toward and from the said mixing drum.

2. A concrete mixer as described in claim 1, wherein the supporting frame includes oppositely arranged bracket members symmetrically related to the axis of the mixing drum, wherein each of these bracket members supports a roller track

means including spaced pairs of superposed roller members, and wherein the legs of the U-shaped frame of the hopper structure are extended between the superposed roller members to be guided thereby.

3. A concrete mixer as described in claim 2, including shifting means for shifting said hopper structure, said shifting means embodying a shaft pivoted to said bracket members below the roller track means mounted thereon and extending at a right angle to the rotary axis of the mixing drum, lever arms on said shaft, link members connecting said lever arms to symmetrically arranged areas of the web portion of the U-shaped frame, and worm drive means mounted on one of said brackets and coupled with said shaft, said worm drive means adapted to effect rotation of said shaft to permit shifting of the hopper structure toward and from the mixing drum.

4. In a concrete mixer a supporting frame, a rotatable mixing drum mounted on said frame and having an axial opening at one end through which the drum is charged and discharged, a shiftable hopper structure including a U-shaped frame having parallelly arranged leg members, a charging hopper mounted on said U-shaped frame including a combined extension and closure member rotatably attached and sealed to said charging hopper, said extension and closure member embodying a tubular extension dimensioned to be extended into the axial opening of the mixing drum and a ring-shaped closure member sleeved upon the tubular extension and secured thereto adjacent the rear end thereof and adapted to effect sealing of the axial opening of the mixing drum when the extension and closure member extends with its tubular extension partly into the mixing drum through the axial opening thereof, and a pair of roller track means on said supporting frame arranged in symmetrical, parallel relation to the axis of the mixing drum, said roller track means engaged with the leg members of the U-shaped frame of the shiftable hopper structure to support and guide same for shifting of the hopper structure toward and from the mixing drum in axial alignment with the axis thereof.

5. A concrete mixer as described in claim 4, wherein the diameter of the tubular extension of the combined extension and closure member is substantially smaller than the diameter of the axial opening of the mixing drum to permit unimpeded entering of the tubular extension in the mixing drum through such axial opening and discharging of concrete from the mixing drum through its axial opening when the ring-shaped closure member is not in sealing position.

6. A concrete mixer as described in claim 4, wherein the combined extension and closure member is rotatably and axially non-shiftably attached to the end of the hopper by combined bearing and sealing means embodying ring-shaped, rotatably and axially non-shiftably interengaged members attached to the rear end of said tubular extension and the lower end of the charging hopper.

7. A concrete mixer as described in claim 6, wherein said combined bearing and sealing means includes an outer bearing and sealing sleeve attached to the combined extension and closure member and assembled from two elongated, intersleeved bearing members shaped and dimensioned to form between said members an elongated, cylindrical inner bearing and sealing chamber, having stop shoulder portions at opposite ends, and a sleeve attached to the end of the

hopper and extended into said sealing chamber, said inner bearing and sealing sleeve including a cylindrical sleeve portion positioned within the sealing chamber between the stop shoulder portions thereof and an attachment sleeve portion mounted on the lower end of said hopper and secured to the cylindrical sleeve portion of said inner bearing and sealing sleeve.

8. In a concrete mixer a supporting frame, a rotatable mixing drum on said frame having an axial opening at one end through which such mixing drum is charged and discharged, a shiftable hopper structure including a U-shaped frame having parallel legs shiftably supported at spaced points by said supporting frame, a charging hopper pivotally supported by said shiftable frame in the plane thereof, a closure rotatably mounted on said hopper arranged to close the opening of the mixing drum when brought into contact therewith, a pair of track means mounted on said supporting frame in symmetrical, laterally offset parallel relation to the axis of the mixing drum adapted to support and guide the U-shaped frame, the charging hopper and the closure of the shiftable hopper structure toward and from said mixing drum in axial alignment therewith, and shifting means for the frame of said shiftable hopper structure, said shifting means mounted on said supporting frame and coupled with the U-shaped frame of the shiftable hopper structure.

9. In a concrete mixer, a supporting frame, a rotatable mixing drum mounted on said frame and having an axial opening at one end through which the drum is charged and discharged, a shiftable hopper structure including a shiftable frame having laterally spaced parallelly arranged legs, a charging hopper pivotally mounted on said shiftable frame and partially extended therethrough between the legs thereof in axial alignment therewith and a closure rotatably mounted on said hopper and arranged to close the opening of said mixing drum when brought into contact therewith, and a pair of track means mounted on said supporting frame in symmetrical, laterally offset parallel relation to the axis of said mixing drum, said track means adapted to support the legs of said shiftable hopper frame at spaced points for guiding said structure and its charging hopper and the closure supported thereby toward and from said mixing drum in alignment with the axis thereof.

10. In a concrete mixer, a supporting frame, a rotatable mixing drum mounted on said frame and having an axial opening at one end through

which the drum is charged and discharged, a shiftable hopper structure including a shiftable U-shaped frame having laterally spaced parallelly arranged legs, a charging hopper vertically, 5 yieldingly tiltably mounted on said shiftable frame, between the legs thereof in axial alignment therewith and a closure rotatably mounted on said hopper and arranged to close the opening of said mixing drum when brought into contact therewith, and a pair of track means mounted on said supporting frame in symmetrical, laterally offset parallel relation to the axis of said mixing drum, said track means adapted to support the legs of said shiftable hopper frame for guiding said structure and its charging hopper and the closure supported thereby toward and from said mixing drum in alignment with the axis thereof.

11. In a concrete mixer, a supporting frame, 10 a rotatable mixing drum mounted on said frame and having an axial opening at one end through which the drum is charged and discharged, a shiftable hopper structure including a shiftable U-shaped frame having laterally spaced parallelly arranged legs, a charging hopper pivotally mounted on said shiftable frame between the legs thereof in axial alignment therewith for tilting in a vertical plane and being additionally yieldingly coupled with the web portion of said shiftable frame to yieldingly counteract vertical tilting of said hopper in said shiftable frame and a closure rotatably mounted on said hopper and arranged to close the opening of said mixing drum when brought into contact therewith, and a pair 15 of track means mounted on said supporting frame in symmetrical, laterally offset parallel relation to the axis of said mixing drum, said track means adapted to support the legs of said shiftable hopper frame for guiding said structure and its charging hopper and the closure supported thereby toward and from said mixing drum in alignment with the axis thereof.
